UNITED STATES PATENT OFFICE.

FRED W. L. FULLERTON, OF MAPLEWOOD, NEW JERSEY, AND MICHAEL A. BELLONE, OF ST. ALBANS, NEW YORK, ASSIGNORS TO FULL-O-LITE COMPANY, INC., OF NEW YORK, N. Y., A CORPORATION OF NEW YORK.

LIGHTING FIXTURE.

Application filed July 7, 1927. Serial No. 203,884.

Our invention relates to lighting fixtures particularly of the character wherein the globe or shade is supported by fingers contacting with its inner surface under the rim 5 with a shell bearing upon the outer surface of the globe or shade to prevent slipping. One object of the invention is to simplify construction and lessen the cost of manufacture; another object is to provide a hanger 10 equally well adapted for use in a suspended fixture or one connected directly with a ceiling; another object is to provide means for focusing the lamp; another object is to facilitate the adjustment of the canopy in ceiling fixtures to give free access to the outlet box and wires at such point without the necessity of removing the canopy or disturbing the fixture. Other objects and advantages of our 15 invention will be apparent by the description following.

In the accompanying drawings:

Figure 1 is a central vertical elevation of a hanging fixture embodying our invention.

Fig. 2 is a front elevation of the yoke 25 detached showing a modification in the manner of supporting the lamp receptacle.

Fig. 3 is a side view of the same.

Fig. 4 illustrates a modified manner of connecting the yoke with the shell, parts being 30 broken away.

Fig. 5 is a side view of the stud upon the top of the yoke, which is shown broken away.

Fig. 6 is a top view of the same, and

Fig. 7 is a central vertical elevation of a 35 ceiling fixture embodying our invention.

Referring to the drawing, we employ a yoke made preferably of a single flat strip of metal bent to the shape shown, that is, having a horizontal top 10, vertical sides 11, 40 curved outwardly as at 12 a predetermined distance below the top, then vertically or nearly so as at 13, then horizontally as at 14, which horizontal portions are inserted within the mouth of the globe or shade 15 forming 45 interior seats for the rim thereof. The ends of the portions 14 are preferably rounded and bent slightly downwardly to conform to the shape of the glassware.

The arms 11 and 12 of the yoke have a certain degree of resiliency.

A stud 16 is secured to the yoke at the center of its top 10 in any suitable manner. We have shown the stud provided with an annular shoulder 17 at its lower part, a re-

duced lower end passing through a central 55 opening in the top of the yoke and upset against the under surface of that member of the yoke.

This stud has a central vertical bore for the passage of the conductor wires, the upper portion of the bore being threaded to receive the exteriorly threaded stem 18 of the ornamental loop 19, to which the chain 20 for suspending the fixture is attached. The stem of the loop is hollow to permit the passage of the 65 wires.

The lamp receptacle 21 is supported against the under side of the horizontal top 10 of the yoke in any suitable manner, preferably by screws 22, which pass through holes in the 70 top 10, provided at either side of the stud 16, for that purpose.

23 denotes a bell-shaped shell of any desired ornamental form provided at its bottom with the customary skirt 24 and annular bead 25. 75 The top of the shell 23 rests upon the top 10 of the yoke being provided with an opening for the passage of the stud 16. The beaded lower edge of the shell 23 rests upon the top surface of the globe or shade 15 so that the 80 glassware is held between the bottom of this shell and the horizontal portions 14 of the yoke.

Where the fixture is employed for indoor use, it is seldom necessary to lock the shell 85 in place upon the glassware, but when used outdoors or in a place exposed to high winds it is preferable that the shell be prevented from accidental movement. To accomplish this, the exterior of the stud 16 may be 90 threaded, and a lock nut 26 screwed thereon down upon the top of the shell 23 as shown in Fig. 4.

We prefer, however, instead of forming a continuous thread upon the stud 16, to cut 95 it away on two opposite sides of the stud providing vertical grooves 27 as shown most clearly in Figs. 5 and 6, and to provide oppositely placed threaded vertical lugs 28 upon the top of the shell 23 for engagement with 100 the spaced sections of thread upon the stud 16, these lugs passing into the grooves 27 when the stud is pushed through the opening in the top of the shell in connecting the shell to the yoke. When the top of the shell comes 105 into contact with the top of the yoke, it is only necessary to give either the shell or the yoke a partial rotation to bring the threads

on the lugs into engagement with the threads on the stud whereby the shell and yoke are held together. In order however to prevent any chance of accidental separation of the shell and yoke, we prefer to employ a ring nut 29 which is screwed over the stud 16 down upon the top of the lugs 28. These lugs may be secured to the shell by solder or in any other suitable way.

6 While in Fig. 1 we have shown the lamp receptacle 21 fixed to the yoke and so hereinbefore described it, it is sometimes desirable to be able to adjust the lamp relatively to the globe for focusing purposes, and to provide 15 means for so doing we employ an adjustable bracket 30 composed of a flat strip of metal with upturned ends 31, of a size to fit between the sides 11 of the yoke in each of which side is formed a vertical slot 32 through which 20 pass short set screws 33 the ends of which enter threaded holes in the upturned ends 31 of the bracket 30 whereby the bracket may be raised or lowered to the desired position and there held by tightening the screws 33. The 25 horizontal bottom of the bracket 30 is provided with holes for the passage of screws for holding the lamp receptacle against it. This construction is illustrated in Figs. 2 and 3 of the drawing. It will be readily understood 30 that the receptacle 21 may be easily transferred from its fixed position on the yoke to position on the bracket, or that the bracket may be swung out of the way of the lamp when the lamp is connected with the receptacle fixed 35 to the yoke. The bracket may be easily detached from the yoke simply by removing the screws 33, or without the removal of the screws by drawing the screws through downwardly inclined open ended slots 34 connected 40 with the slots 32 at their upper ends. This is illustrated in Figs. 2 and 3.

In Fig. 7 of the drawings we have illustrated our invention applied to a ceiling fixture. In this connection we employ a strap 35 45 preferably formed from a flat strip of metal provided with an opening through which passes the ordinary threaded tube 38 in the outlet box 39, a lock nut 40 being screwed over the threaded tube 38 up against the strap 35 50 to hold the strap in place against the ceiling. This lock nut 40 may have a knurled outer surface, or be of hexagonal shape for engagement by a wrench. The stud 16 on the yoke is screwed upon the tube 38 thus supporting 55 the yoke and connecting it with the outlet box. The lower part of the shell 42 is of the same shape as the lower part of the shell 23 and for the same purpose, but the top of the shell 42 is open for the passage of the yoke 60 therethrough. As is customary in ceiling fixtures we employ a canopy 43, but which is so connected that free access to the outlet box and wires at such point may be had without the removal of the canopy or disturbance of 65 the fixture.

The lower open end of the canopy 43 is of slightly larger diameter than the neck 44 of the shell 42 over which it fits.

The canopy 43 is held up against the ceiling by screws 45, which pass through holes in the strap 35, and project through holes in the bottom of the canopy upon which projections are screwed ornamental knobs or nuts 46.

It will be apparent that by removing the knobs 46 from the screws 45 the canopy 43 75 will drop or may be lowered until its lower end rests upon the shell 42 thereby leaving an open space between the top of the canopy and the ceiling permitting access to the outlet box and wires for the purpose of connecting the wires or for repairs.

We claim as our invention:

1. In a lighting fixture, a globe support comprising a yoke consisting of a single flat strip of material shaped to form a horizontal top with depending sides having out-turned lower ends adapted to enter the mouth of the globe at opposite sides thereof, a lamp receptacle fixed to the underside of the horizontal top of the yoke, and a shell covering the yoke 90 and seated upon the outer surface of the globe.

2. In a lighting fixture, the combination of a yoke consisting of one piece of material shaped to form a horizontal top provided with a central opening and having depending sides with out-turned lower ends adapted to enter the mouth of a globe at opposite sides thereof, a stud secured to the yoke within said opening in its top, a lamp receptacle fixed to the underside of the horizontal top of the yoke in alignment with said opening, and a shell having an opening in its top through which said stud extends, the bottom of said shell being seated upon the outer surface of the globe.

3. In a lighting fixture, the combination of a yoke consisting of one piece of material shaped to form a horizontal top provided with a central opening and having depending sides with out-turned lower ends adapted to enter the mouth of a globe at opposite sides thereof, a stud secured to the yoke within said opening in its top, a lamp receptacle fixed to the underside of the horizontal top of the yoke in alignment with said opening, a shell having an opening in its top through which said stud extends, the bottom of said shell being seated upon the outer surface of the globe, and means engaging said stud for holding said shell in such position.

4. In a lighting fixture, the combination of a yoke consisting of a single piece of material shaped to form a horizontal top provided with a central opening and having depending sides, the lower ends of which are out-turned and adapted to enter the mouth of a globe at opposite sides thereof, a stud secured to the yoke within said opening in its top, the outer surface of the stud being pro-

vided with spaced, aligned sections of threads, a shell provided at its top with an opening for the passage of said stud, oppositely disposed vertical lugs provided with threads at their facing surfaces secured to the shell and adapted to enter the spaces between the threads on the stud when it is passed through the opening in the shell, whereby the threads on the lugs will engage the threads on the stud when either the stud or shell is given a partial rotation, the bottom of said shell being seated upon the outer surface of the globe.

Signed by us this 30th day of June 1927.

FRED W. L. FULLERTON.

MICHAEL A. BELLONE.
